(57) **CLAIM**

The ornamental design for a bone punch, as shown and described.

DESCRIPTION

FIG. 1 is a front perspective view of a bone punch.

FIG. 2 is a front view of the bone punch of FIG. 1.

FIG. 3 is a rear view of the bone punch of FIG. 1.

FIG. 4 is a left side view of the bone punch of FIG. 1.

FIG. 5 is a right side view of the bone punch of FIG. 1.

FIG. 6 is a top view of the bone punch of FIG. 1; and,

FIG. 7 is a bottom view of the bone punch of FIG. 1.

The broken lines shown in FIGS. 1-7 illustrate a symbolic break in length. The appearance of any portion of the bone punch between the break lines forms no part of the claimed design.

1 Claim, 7 Drawing Sheets
